LIVING ROOM FOLDING BED

Filed Dec. 13, 1926

PER *Albert J. Gipe*
ATTORNEY.

UNITED STATES PATENT OFFICE

ERICK GOTTFRID WIKMAN AND CLARA CARLSON, OF CHICAGO, ILLINOIS

LIVING-ROOM FOLDING BED

Application filed December 13, 1926. Serial No. 154,536.

This invention relates to improvements in living room folding beds, and has for one of its principal objects the provision of a folding bed or the like which can be used in a living room during the day, serving as a book case, and which at night can be taken down to make a comfortable bed.

One of the particular objects of this invention is to provide, in a folding bed adaptable for use in a living room as a book case, means for the actual insertion of books in the same so that its purpose may be twofold, while at the same time producing a structure which will efficiently meet the requirements of both a bookcase and a bed.

Still another and further important object of this invention is the provision, in a folding bed or the like, of means for a double folding of the bed and its contained springs, mattresses and the like with a minimum expenditure of time, trouble, and inconvenience.

Another and still further important object of this invention is to provide, in a combination piece of furniture for a living room or the like, a bookcase and a bed which is economical of manufacture, simple of construction, and therefore readily operated.

Other and further important objects of the invention will be apparent from the disclosures in the accompanying drawings and following specification.

The invention, in a preferred form, is illustrated in the drawings and hereinafter more fully described.

In the drawings:

Figure 1 is a perspective view of the improved combination book case and folding bed of this invention, showing the same in closed position.

Figure 2 is a side elevation showing the bed opened out, and with the operation disclosed in dotted lines.

Figure 3 is a view somewhat similar to Figure 2, illustrating a slight modification of the invention.

Figure 4 is a detail view of the spring employed in the bed, showing the special construction used in the folding over arrangement.

As shown in the drawings:

The reference numeral 10 indicates generally a case for the combined folding bed and book rack of this invention, which, as shown, can be made of any desired material and numerous designs. Rollers 12 are preferably provided in the bottom thereof so that the same may be readily moved from place to place.

At the top of the case 10 is provided a series of doors 14 preferably having glass 16 therein, these doors being mounted to cover a shelf or series of shelves adapted to contain books or the like. Larger doors 18 are provided over the lower and larger portion of the structure behind which the folding bed is concealed when the device is not in use as a bed.

As shown in Figure 2, the bed structure itself comprises rails 20 and 22, foldably mounted with respect to each other by means of a spring hinge or the like 24. Adjacent the hinge 24 is a pair of legs 26 which act to support the middle of the bed when in open position, these legs having mounted at the upper end thereof a bracket 28 into which is inserted corresponding projections 30 of the bed rails 20 and 22. A bracket in the form of a pivoted lever 32 supports the legs 26, and this bracket may be swung about its pivotal point 34 as shown by the dotted lines in Figure 2 so that the legs 26 may be folded back under the bed when not in use.

The outer and forward edge of the bed comprising the rails 22 is likewise supported by foldable legs, as shown at 36, mounted on a pivoted bracket 38, and the head of the bed 40 is foldable downwardly and rearwardly as shown by the dotted lines.

A hook member 42 is provided at this point for connection with a corresponding pin 44 at the rear end of the rails 22, so that the bed itself may be locked in folded position for stowing away in the body of the case 10.

A foldable spring, as shown at 46, is adapted to be used with this modification of the bed, this spring being formed in two portions connected adjacent the center of the bed by means of a series of coiled springs 48, 100

whereby the same can be readily folded in conjunction with the bed rails 22.

For box springs a slightly different construction is provided as shown in Figure 3, the box spring itself as at 50 being hinged or jointed in the middle as shown at 52, adapted for a folding over upon itself as illustrated in the dotted lines in this figure. When this folding has been accomplished the rails 54 and 56 of the bed are telescoped into each other by simply sliding the forward rails 56 rearwardly, a pin 58 being provided to prevent any undue forward motion of the rails 56. The legs 60 are then folded under the bed rails in the same manner as described in connection with Figure 2, and a suitable lock member in the form of an adjustable pivoted hook or the like 62 is provided at the rear of the rails 54 in order that the mattress 50 may be properly maintained in folded relation. An adjustable strap 64 is also provided for the maintenance of the pillows, blankets, etc., when the bed is to be folded.

It will be seen that herein is provided a folding bed or the like which constitutes an ornamental and useful adjunct to any living room in addition to comprising an economical and useful piece of furniture. The operation is extremely simple, and there is no danger of accidental folding while the bed is occupied. The device as shown comprises a suitable double bed, but obviously may be made in other sizes, as desired.

We are aware that many changes may be made and numerous details of construction varied throughout a wide range without departing from the principles of this invention, and we therefore do not purpose limiting the patent granted thereon otherwise than as necessitated by the prior art.

We claim as our invention:

A folding bed frame comprising at each side a pair of rigid side bars, means hingedly connecting together adjacent ends of the side bars, lugs depending from each of the said adjacent ends, a socket detachably receiving the lugs and preventing their separation, a supporting leg rigid with the socket, a pivoted link connecting the leg foldably with one of the side bars, the hinge means comprising resilient extensible elements whereby when the lugs are removed from the sockets the frames may be folded upon each other in spaced relation to receive a mattress therebetween.

In testimony whereof we affix our signatures.

E. GOTTFRID WIKMAN,
CLARA CARLSON,
